(57) **CLAIM**

The ornamental design for vending machine with slide, as shown and described.

DESCRIPTION

FIG. 1 is a perspective view of a vending machine front panel and slide.

FIG. 2 is a front view of the vending machine front panel and slide of FIG. 1.

FIG. 3 is a rear view of the vending machine front panel and slide of FIG. 1.

FIG. 4 is a right side view of the vending machine front panel and slide of FIG. 1.

FIG. 5 is a left side view of the vending machine front panel and slide of FIG. 1.

FIG. 6 is a top view of the vending machine front panel and slide of FIG. 1; and,

FIG. 7 is a bottom view of the vending machine front panel and slide of FIG. 1.

In the drawings, the broken lines illustrate environment and form no part of the claimed design.
